 corporation of New York

Application May 15, 1936, Serial No. 79,881

7 Claims. (Cl. 202—169)

The invention relates to apparatus for removing pitch or other coatings from the interior surfaces of containers.

An object of the invention is to provide improved methods and apparatus for removing coatings of soluble material from the inner surface of containers.

A more specific object of the invention is to provide improved methods and apparatus for depitching beer barrels.

Other objects of the invention will be apparent from the following description and the accompanying drawings, in which:

Figure 1 is a view of apparatus suitable for use with this invention, this view being partly in elevation and partly in section on the line 1—1 of Fig. 2;

Fig. 2 is a top plan view of the apparatus of Fig. 1;

Fig. 3 is a vertical section on an enlarged scale of one of the spindles used for introducing vapor into the barrel, the section being taken along the line 3—3 of Fig. 2;

Fig. 4 is a view of a valve used in the operation of the apparatus showing its plunger in a position different from that shown in Fig. 1; and

Figs. 5 and 6 are enlarged views of a three-way valve showing it in two different positions of operation.

In accordance with this invention, the pitch or other lining of containers is removed by the action of a solvent which is introduced into the container in vapor form. The invention will be specifically described in connection with methods and apparatus for the removal of pitch linings from beer barrels, but it is to be understood that the invention is not limited to the treatment of beer barrels and can be used with equal success for the removal of linings from other containers.

Solvent vapor is produced by boiling a suitable solvent in stills 1 and 2 which may conveniently be cylindrical in shape as illustrated in the drawings. The stills may be heated in any convenient way. In the drawings steam coils 3 are shown in the stills for the purpose of heating the solvent in the stills. Outlets 4, furnished with valves 5, are provided for draining the stills. Each still is desirably provided with a gauge glass 6 for indicating the liquid level, and with a safety device to prevent explosions due to the building up of excessive pressure. Since the pressures involved are small, the safety device for still 1 may conveniently consist of a pipe 7 leading from the vapor space in this still to a trap 8 which is preferably mounted next to the condenser 9. The trap

communicates at 10 with the vapor space in the condenser. Vapor flowing from the still to the trap condenses to a liquid which sets up a static pressure head and prevents further flow of vapor unless the pressure in the still becomes excessive, in which case it can blow vapor through the liquid in the trap and through opening 10 into condenser 9. Another pipe 11 leads from still 2 to a similar trap mounted behind the one shown in the drawings.

The traps serve not only as safety devices but also as devices to maintain a substantially constant pressure in the still. The rate of heat input is so adjusted as to generate vapor somewhat more rapidly than it is used for depitching. This insures that there will also be sufficient pressure, while excess pressure is prevented by escape of vapor through the traps. A manometer 12, or other suitable pressure gauge, may be provided for each still for showing the excess of vapor pressure above the atmospheric pressure.

From the stills 1 and 2, vapor lines 13 and 14 provided with valves 15 and 16 respectively, lead to a solvent vapor header 17 which extends longitudinally of the apparatus. Condensate return lines 18 and 19 provided with valves 20 and 21 connect the stills 1 and 2 respectively to a longitudinally extending condensate header 22.

For each barrel cleaning station there is provided a valve 23 opening into a spindle 24 upon which the barrel 25 rests. Pipes 26 and 27 lead from valve 23 to the solvent vapor header 17 and the condensate header 22 respectively. The pipe 26 leading to the vapor header is desirably provided with a loop 28 to keep condensate from running into the vapor header. The pipe 27 should be so arranged as to permit drainage from the valve 23 to the condensate return header 22.

The spindle 24, upon which rests the barrel to be cleaned, is shown in detail in Fig. 3. It consists of an outer tube 29 tapered at its upper end to provide a conical seat 30 to engage with the metal 31 which defines the bung hole of the barrel 25. Asbestos packing 32 is provided on the conical seat 30 to insure a tight joint. A separating tube 33 is mounted within the outer tube 29, and within the separating tube there is provided an air vent tube 34. As shown in Fig. 1, the air vent tube 34 is desirably of such length as to reach nearly to the upper inner surface of a barrel 25 resting on the conical seat 30. The air vent tube may desirably be made extensible to provide for rapid adjustment to suit barrels of differing dimensions. Rods or bars 35 running from the conical seat 30 to the air vent tube 34 form an

open centering cone to guide the barrel to the seat 30. Around the outside of the tube 29 a drip trough 36 is provided to catch any liquid or vapor which may leak through the joint between the barrel and the seat 30. A pipe 37 conveys the liquid or vapor caught by the drip trough to a condenser 9 where the vapor is condensed.

The valve 23 has valve seats 38 and 39 and a plunger 40 with tapered ends adapted to seat 10 against the valve seats 38 and 39. Pipe 41 leads from the valve 23 to the condenser 9, and also communicates by means of pipe 42 with the air vent tube 34. The valve plunger 40 is secured to rod 43 which passes through stuffing box 44. 15 Operating lever 45 engages with the outer end of rod 43 and serves to move the plunger from one position to another. A valve seating spring 46 is provided to hold the plunger 40 tightly in engagement with the valve seat to which it is 20 moved by the lever 45.

As shown in the drawings, the lever 45 is desirably continued to a position over the barrel 25 so that removal of the barrel from the spindle 24 is impeded or prevented while the operating lever is in such position as to admit solvent vapor from pipe 26 to the spindle.

The condenser 9 is provided with cooling coils 47 for the circulation of water or other cooling medium and with a gauge glass 48. The condenser has a cover 49 provided with an opening 50 to permit the escape of air from the condenser and the introduction of liquid solvent into it. A pipe 51 leading from the bottom of the condenser communicates through valves 52 and 35 53 with condensate lines 18 and 19 leading to the stills 1 and 2. A drain 54 with a valve 55 opens into the condenser 9 at a level slightly above the highest level reached by the pipe 51, and another drain 56 with valve 57 is desirably 40 provided at the bottom of the condenser to permit the complete drainage of its contents.

A housing 58 is desirably provided to enclose the apparatus. The top of the housing forms a convenient working platform. It may also be 45 desirable to include an insulating wall 59 to separate the hot stills from the cold condenser.

While the apparatus illustrated in Fig. 2 has four barrel cleaning stations, it is to be understood that the invention is not limited thereto 50 and that any suitable number of stations may be used.

Trichlorethylene is a suitable solvent for removing many kinds of pitches from beer barrels, but other suitable solvents or mixtures may 55 be used if desired.

The two stills used in the apparatus provide a means for separating the solvent from the dissolved pitch without interrupting in any way the continuity of operation for cleaning barrels. 60 Assuming that the apparatus is to be placed in operation, solvent is charged into the condenser 9 to fill the lower portion and to run through pipe 51 and valve 52 into still 1. Valve 53 is closed to prevent solvent from running into still 65 2. When the gauge glass 6 shows that a sufficient quantity of solvent has been run into still 1, the charging of solvent is discontinued. Valves 16 and 21 are closed; valves 15 and 20 are opened. Barrels to be cleaned are placed on the spindles 70 24 and the operating levers for those spindles over which barrels have been placed are moved so as to give them and valve plungers 40 the positions indicated in Fig. 1.

Beer barrels have two openings; the bung hole 75 and the tap hole. The bung hole is placed over

the spindle while the tap hole is closed by a cork during depitching of the barrel.

Cooling water or other cooling medium is turned into coils 47 of the condenser 9, and steam into coils 3 of still 1. Solvent vapor from still 5 1 passes through valve 15 and vapor line 13 to the vapor header 17, and from there through the pipes 26 to the individual barrel cleaning stations. Upon arriving at a station at which the valve plunger 40 is in the position indicated 10 in Fig. 1, the vapor then rises through spindle 24 to reach the interior of barrel 25. The air present in the barrel when it was inverted over the spindle is forced through air vent tube 34 and tubes 42 and 41 to the condenser 9 where solvent 15 vapor entrained with the air is condensed.

The provision of an air vent tube to permit the escape of air from the interior of the container is an important feature of the invention. Without a vent tube the solvent vapors act upon 20 the pitch lining very much more slowly than when it is present. While the vent tube is provided primarily for the escape of air, in case vapor is being introduced into the container faster than it is being condensed therein, some 25 vapor will also pass out through the vent tube and reach the condenser 9 where it will be condensed. Since the vapors of the solvents preferably used in connection with this invention are heavier than air, it is apparent that with the 30 air vent tube located as in Fig. 1, the air in the container will be forced up while resting on the heavier solvent vapors and will be substantially all expelled if the air vent tube reaches nearly to the top of the barrel. This leads to rapid 35 action of the solvent vapor upon all parts of the pitch lining.

The hot solvent vapor striking the interior of the barrel 25 is condensed and dissolves the pitch 40 lining of the barrel.

The barrel is cold when placed upon the machine and because it is cold condenses the vapor impinging upon its inner surface. The condensation of the vapor raises the temperature of the barrel, but since this is continually losing heat to its surroundings, vapor will continue to condense to make good the loss of heat from the barrel. The speed with which pitch is removed has been materially increased by directing an air blast against the outer surface of the 50 barrel. The air blast removes heat from the barrel more rapidly and results in an increased rate of condensation of vapor upon the inner surface of the barrel.

The condensed solvent and dissolved pitch run 55 down the inner surface of the barrel and through the spindle 24 to the valve 23. The separating tube 33 located inside the outer tube 29 of the spindle provides for a free passage of vapor up into the barrel unobstructed by condensate running down. From valve 23 the condensate runs through pipe 21 to the condensate header 22, and from there through valve 20 and pipe 18, back into still 1.

After the barrel has been subjected to the action 65 of the solvent vapor for a sufficient time to entirely dissolve and remove the pitch lining, the operating lever 45 is moved back to throw the valve plunger 40 into the position shown in Fig. 4. In this position the plunger 40 seats on valve seat 70 38 and prevents the entrance of solvent vapor to the barrel. The cork closing the tap hole of the barrel is then removed. Since the vapor of such solvents as trichlorethylene, carbon tetrachloride, or many other suitable solvents are material- 75

ly heavier than air, the solvent vapor falls through the spindle 24 and pipe 41 to the condenser 9 where the vapor is condensed. The barrel is at the same time filled with air drawn in through the tap hole. The barrel is then removed from the spindle, another barrel is placed onto the spindle and the cycle is repeated.

In using trichlorethylene for the removal of a high melting pitch from half barrels, it has been found that a treatment of the lining with solvent vapor for a period of about ten minutes is ordinarily sufficient to insure its complete removal. The barrel is allowed to remain upon the spindle for a further period of about one minute to permit the drainage of the solvent vapor from the barrel.

In some cases it may be desired to use the method and apparatus of this invention for the depitching of barrels which have only one opening instead of two openings as is customary with beer barrels. In such cases the opening of the barrel is placed on the spindle 24. As there is no tap hole to be opened, drainage of the solvent vapor from the barrel would be very slow if it were not for the three-way valve 60. When the valve plunger 40 is in the position shown in Fig. 1, the three-way valve 60 is in the position indicated in Fig. 5. When the valve plunger 40 is in the position indicated in Fig. 4, valve 60 is turned to the position shown in Fig. 6. In this position, communication with pipe 42 is shut off, and a slow stream of air from air line 61 is passed up through air vent tube 34 to force the solvent vapor down through spindle 24 and into condenser 9. In many cases it will be sufficient if the valve 60 merely opens to the atmosphere instead of to the air line 61, but for greater rapidity of action the air line may be used. At most it should supply only a gentle stream of air as otherwise air and solvent vapor may be forced into and out of the condenser faster than the solvent can be condensed, resulting in an undesirable loss of solvent. For the treatment of beer barrels with two openings, the valve 60 is not necessary as was previously pointed out. When valve 60 is provided it is desirably connected by mechanism not shown in the drawings to lever 45 so as to be operated in synchronism with valve plunger 40.

Continued operation of the device results in the accumulation of dissolved pitch in still 1. As the pitch gradually accumulates in the still the temperature of the still should be gradually increased to maintain substantially the same vapor pressure. This has no deleterious effect upon the effectiveness of the device for depitching barrels since the pitch does not materially vaporize and only relatively pure solvent vapor is supplied to the spindles 24, but the dissolved pitch must of course be removed from the system from time to time. When it is desired to do this, valves 20 and 52 are closed while valves 21 and 53 are opened. Condensate from the condensate header 22 and condenser 9 is now returned to still 2 instead of to still 1. When a sufficient amount of condensate has collected in still 2 to cover the steam coils 3 in this still, steam is admitted to these coils and valve 16 is opened. Both stills now supply vapor but the condensate is returned entirely to still 2. Continued operation results in the expulsion of practically all of the solvent from still 1 which will ultimately contain nothing but pitch. With valve 15 left open the pitch in still 1 can be drained off by opening valve 5 in drain 4. Valve 5 should desirably be closed as soon as vapor begins to come off. In due course

of time, the pitch which collects in still 2 is removed in a similar manner. It will be noted that the distillation of solvent from the pitch and the removal of the pitch does not interfere in any way with the continued use of the machine for depitching barrels.

It is not infrequently found in depitching beer barrels that these contain an appreciable amount of water or water vapor. This water condenses in the condenser 9 and being lighter than the usual solvents which are suitable for use in connection with this invention, forms a layer above the solvent in the condenser. It can be drawn off at suitable intervals through drain 54 by opening valve 55. It is important that the water be drained off at intervals and kept from accumulating to a sufficient extent to enter into the stills. The presence of water vapor along with the solvent vapor materially reduces the rate at which the pitch is dissolved and removed from the barrel.

There will normally be a slight loss of solvent in the use of this apparatus. The loss is made good by suitable additions of solvent to the condenser.

I claim:

1. An apparatus for removing a pitch or similar lining from the interior of a container which comprises a pair of stills for boiling a solvent which dissolves the lining; means for heating the stills; vapor lines provided with valves to conduct solvent vapor from the stills to the container; condensate return lines provided with valves for conducting condensed solvent vapor and dissolved lining back from said container to the stills; control means connected to said lines to admit solvent vapor to the container and to permit condensed solvent to return to the stills when said control means have one operating position, and to prevent access of solvent vapor to the container or return of condensed solvent to the stills but to permit passage of solvent vapor from the container to a condenser when said means have a second operating position; a condenser; a pipe connection between said control means and said condenser; a vent tube to conduct air and solvent vapor from the interior of the container to the condenser; and a pipe connection provided with valves to return solvent from the condenser to the stills.

2. In an apparatus for the removal of a pitch or similar lining from the interior of a container, a spindle for admitting solvent vapor into the container, said spindle comprising an outer tube provided with a seat to engage with an opening in the container, an inner tube arranged to separate solvent vapor entering the container from condensed solvent draining from it, and a vent tube disposed within said inner tube to permit the escape of air and solvent vapor from the container.

3. In combination with a spindle as described in claim 2, a condenser, a pipe joining said condenser to the vent tube in the spindle, and a valve arrangement in said pipe, said valve arrangement being adapted to permit free communication between the air vent tube and the condenser when in one position, and to shut off the condenser and open free communication between a source of air and the vent tube when in a different position.

4. In an apparatus for the removal of a pitch or similar lining from the interior of a container, a spindle for admitting solvent vapor to the interior of the container, said spindle comprising

- 5 an outer tube provided with a seat to engage with an opening in the container, an inner tube mounted within said outer tube and spaced therefrom to separate solvent vapor entering the
5 container from condensed vapor draining from it, a vent tube disposed within said inner tube to permit the escape of air and solvent vapor from the container, and a drip trough arranged outside the outer tube to catch vapor and sol-
10 vent which may leak through the joint between the spindle and the container and to deliver such vapor and condensed solvent to a tube which conveys it to a condenser where the vapor is condensed.
15 5. In an apparatus for the removal of a pitch or similar lining from the interior of a con- tainer, the combination of a spindle for intro- ducing solvent vapor into the interior of the con- tainer and for draining away solvent condensed
20 therein, a valve to admit solvent vapor to the container and to permit the drainage of con- densed solvent therefrom when in one position and to prevent access of solvent vapor to the container when in a different position, and means
25 to control the position of said valve, said control means being arranged to impede the removal of a container from the spindle when the valve is in position to admit solvent vapor to the spindle.
30 6. In an apparatus for the removal of a pitch

or similar lining from the interior of a container, a spindle for admitting solvent vapor into the container, said spindle comprising an outer tube provided with a seat to engage with an opening in the container and an inner tube disposed within said outer tube and arranged to separate solvent vapor entering the container from con- densed solvent draining from it and a conduit in the spindle for removing air from the container as vapor enters the same.

7. An apparatus for the removal of pitch or similar lining from the interior of a container which comprises two stills for boiling a solvent for the lining, means to conduct solvent vapor to the container, conduits connected with said means leading from each of said stills, means to control the flow of solvent vapor through said conduits, a vent for the escape of air from the container, means to conduct condensed solvent vapor from the container, conduits connected with said last named means leading to each of said stills, and means to control the flow of condensed solvent vapor through said last named conduits, said control means being disposed to establish communication alternately between said container and each of said two stills to permit removal of accumulated pitch from the inactive still without disrupting the continuity of opera-
